Richard F. Thornton and Charles A. Blankenburg, Chicago, Ill.

Application March 15, 1934, Serial No. 51,072

Term of patent 7 years

To all whom it may concern:

Be it known that we, RICHARD F. THORNTON and CHARLES A. BLANKENBURG, citizens of the United States, both residing at Chicago, county of Cook, and State of Illinois, have invented a new, original, and ornamental Design for a Cabinet for a Fortune Telling or Amusement Device, of which the following is a specification, reference being had to the accompanying drawing, forming part thereof, in which—

Figure 1 is a plan view;
Fig. 2 is a side elevation; and
Fig. 3 is a front elevation of the cabinet for a fortune telling or amusement device showing our new design.

We claim:

The ornamental design for a cabinet for a fortune telling or amusement device, as shown.

RICHARD F. THORNTON.
CHARLES A. BLANKENBURG.
